LEO PAWLICEK, OF MODLING NEAR VIENNA, AUSTRIA, ASSIGNOR TO RABL & GRÜN, OF VIENNA, AUSTRIA, A PARTNERSHIP COMPOSED OF JOSEF JOLLES, ALFRED GRÜN AND OTTO RABL

FRAME FOR HAND BAGS AND LIKE CONTAINERS

Application filed March 23, 1932, Serial No. 600,805, and in Austria February 9, 1932.

This invention relates to a closing frame for bags of all kinds, such as ladies' hand bags, wallets, attaché cases, cigarette cases, powder boxes, special containers, receptacles and holders made of leather, cloth, paper and the like. The invention consists substantially in that the halves of the frame themselves form the opening and closing means and provide a spring clamp closure, so that no separate closing or locking element is required. The clamp closure is preferably formed by suitably interengaging the frame arms arranged on one and the same narrow side of the bag, so that the two frame webs are resiliently held together when the bag is closed, and the closure can be opened by merely exerting pressure against the cooperating arms, but will not come open accidentally as by dropping on a hard surface. The frame may extend the entire height of the bag and serve as frame for the bag.

Several embodiments of the invention are illustrated by way of example in the accompanying drawings in which:—

Fig. 1 is a perspective view showing the frame in open condition.

Figs. 2 and 3 are part perspective views showing modified forms of construction.

Fig. 4 is a perspective view showing a bag fitted with a frame in open condition.

Fig. 5 is an end view of Fig. 4, the bag being shown in full lines in closed condition and in dotted lines in open condition.

Fig. 6 shows a detail in top plan view.

Fig. 7 shows a method of fastening the frame to the bag.

Figs. 8 and 9 show a bag in end elevation fitted with a frame.

Fig. 10 shows a detail of Fig. 9.

Figs. 11 and 12 show further possibilities of construction.

In the forms of construction illustrated each frame half consists of two arms 3 and 4 extending the entire height of the bag, the arms of each half being interconnected by a web 6 extending the entire length of the bag. The frame arms 3 and 4 arranged at each narrow side of the bag are hingedly connected by a pin 5 and curved near this pin.

As shown in Fig. 1, the two arms 4 of one

frame half extend over the arms 3 of the other frame half, the outer arms 4 resiliently pressing against the inner arms 3. If the frame in open position (Fig. 1) is gripped on the webs 6 or on the upper portions of the arms 3, 4 and these are pressed together, the outer arms 4 slide over the inner arms 3 until the frame webs 6 lie directly side by side. In this position every two coacting arms cross near the point of transition near the webs and mutually hold one another. If it is desired to open the frame or the bag, the cooperating frame arms 3, 4 are gripped with the hand below their point of intersection, that is near the middle, and pressed the one towards the other. Owing to the leverage thus exerted the webs 6 are forced apart and the bag is partly opened. If the webs 6 are then gripped with the hand and moved further apart, the bag can be completely opened.

The upper ends of the two cooperating arms may be set off on their opposite surfaces, so that the two arms have each a step-shaped catch r_1 or r_2 (Fig. 2) which interengage when the frame is closed. The inner arms 3 may also each be provided with a catch r_1 and the outer arms 4 with a corresponding enlargement k (Fig. 3). The enlargement k forms a kind of ramp surface when closing the frame, said surface slightly spreading the arms during the closing movement, so that the outer arms snap into the catches in the inner arms under stronger spring action.

The cooperating arms 3, 4 may, for the same purpose, each be provided with a kink or bent out portion 7 (Fig. 6) instead of the steps r_1, r_2 .

The bag (Figs. 4 to 6) consists in known manner of two walls forming the sides and bottom and united on the narrow sides by gussets to complete the bag shape. The frame is so arranged, that the hinge point lies on the bottom of the bag. The webs 6 are fixed to the upper edge of the bag walls 1.

The bag is closed and opened in the manner described in connection with Fig. 1. When passing from the open position (Fig. 4) into the closed position (Fig. 5), the bag is gripped at the portion carrying the webs 6 or laterally thereof at the upper ends of the

arms 3, 4 and pressed together whereby the frames are closed.

It is only necessary to exert pressure on the middle of the arms in order to disengage 5 the fastening and open the bag.

The webs 6 may project from the walls of the bag and be shaped so as to form an angular, circular or curved handle. The walls of the bag may also surround the webs 6 only

10 at separate points or only near the gussets 2, whereas the webs project from the bag walls or extend along these walls.

According to Fig. 7 sleeves 8 are slipped 15 over the webs 6. These sleeves are provided with straight bars 8' to which the upper edge portions of the bag walls 1 are sewn. Each sleeve 8 may consist of several part sleeves between which free sections are left.

The frame arms may be of any desired 20 cross section, for example they may consist of round or flat bars. However, the middle portion of the arms is preferably flattened also when using round bars, so that the two cooperating arms, on being mutually shifted, 25 guide one another, thereby facilitating the opening and closing of the bag. It is evident, that the shape of the frame arms can be adapted to the actual purpose of use. Thus, for example in the case of cigarette cases or other 30 containers substantially of prismatic form, the arms are not curved near the hinge point but are bent at an angle at the top or bottom.

According to Fig. 8 the two arms 3 and 4 of 35 one side gusset are of unequal length, the arm 4' for example being extended at an intermediate point within the range of the other arms 3 so that the hinge point 5 which is then arranged laterally connects a short arm 3 to a longer arm 4.

In the form of construction illustrated in Fig. 9 the arms 3 and 4 are connected by a resilient intermediate part 10, the resiliency being arranged either in the sense of the closing movement or of the opening movement of 45 the bag. If the resilient intermediate elements tend to close the bag arrangements must be provided for holding the bag in a certain opened position. This may for example be effected by providing a catch *r* on the arms 50 4, into which catch the counter arm 3 snaps and thus holds the bag in open position (Fig. 10).

In the form of construction illustrated in 55 Fig. 11 the arm 4 is widened in band-shape and the rod-shaped counter arm 3 connected thereto by a hinge 5, the arm 3 being slideable in a slot 4^d in the arm 4 and can snap into a notch 4^e in closing position.

60 The new frame may also be constructed for bags of two or more parts. Fig. 12 shows such a construction for a two-part bag. In this instance the two arms 3 and 4 with their connecting bars 6 are hinged to a middle frame part at 17. This middle frame part

70 consists of a web 19 which preferably projects slightly above the webs 6 and can form a handle, and of two arms 16. The frame parts 16 may consist of a wide metal band which is slotted in the middle, the arms 3 and 4 sliding in this slot. This wide band-shaped middle part serves for reinforcing the bag and it may be engraved or chased for decoration.

75 In the forms of construction above described the clamping effect during the closing of the bag occurs on the arms of the frame proper. It is evident however that the arrangement may be such that the webs 6 resiliently engage the one over the other in closed position and thus clamp. The frame web may also be provided with a fastening which automatically closes when closing the bag.

80 In the case of resilient connection of the frame parts it is evident that the entire frame in all the forms of construction described may be made together with the arms and webs and any middle parts of a single suitably shaped resilient element. Articles provided with frame members made in accordance with the invention are strong, light, readily opened and closed, free from projecting snaps or movable fastenings, and securely held closed against accidental opening as 85 when dropped or struck.

90 I claim:—

100 1. A portable receptacle including a bag and a frame therefor, said bag having side walls and externally concave gussets at the ends of the bag, said side walls and gussets having reinforcing seam portions inter-connecting the same along the ends of the side walls, said frame having means including a plurality of sets of arms, the arms of each set 105 crossing each other so that pressure exerted on said arms for moving the same toward each other causes an opening movement of said receptacle, said arms having portions resiliently engaging each other and being disengageable by said pressure, each set of said arms being positioned within the concave space of a gusset externally of the bag and in proximity to adjacent reinforcing seams, 110 whereby said pressure is exerted through said side walls and adjacent portions of the gussets in proximity to said reinforcing seams.

115 2. A holder having openable and closable sides with openable end edges at least at one end edge thereof, said edges being movable toward each other to some extent at least when the holder is in a closed condition for opening the holder, said edges overlying two elemental portions of two rods with the elemental portions movable toward each other, 120 said rods crossing each other in such manner that each respective rod engages the top edge of the opposite side of the holder, said rods beyond the aforesaid elemental portions to- 125

ward the bottom of the holder being engaged with each other by a pivotal connection and said rods being so located as to be unobstructed in their movement by the contents of the 5 holder.

3. A holder having a metal frame and front and back cover portions of flexible material openable and closable about the bottom edge, said frame comprising complementary 10 bow shaped members hinged together at their extremities and crossing intermediate their ends, the middle portions of said members being secured to the top edge of opposite cover portions, respectively, the crossing portions 15 interengaging to retain the frame in closed position by snap action, and said crossing portions being accessibly disposed between the side edges of said cover portions to permit of ready manipulation thereof by 20 manual pressure applied thereto.

4. As a means for relatively shifting the opposite side walls of a holder between open and closed positions by pressure exerted in the same direction on such side walls, a pair 25 of arms hingedly connected at one end and each having the opposite end adapted to be secured to a side wall adjacent the top of the latter, each arm having a configuration such that the arms when in the closed position of 30 the holder will present the arms as crossed adjacent such secured ends, the assembly being such that when the arms are secured to the side walls the crossing point will be shifted toward the hinge connection during opening 35 movement of the holder, the arms carrying relative formations such that when the holder is in closed position the formations will retain the holder closed, said formations being rendered inactive by movement of the 40 arms to open the holder and rendered active by movement of the arms to closed position.

5. A holder having openable and closable sides, a frame structure between the sides including a central inverted U-shaped frame, 45 a pair of lateral inverted U-shaped frames hingedly connected at their lower ends to the lower ends of the side portions of the central frame and the side portions of the lateral frames crossing each other with the upper end of each lateral frame attached 50 respectively to a side of the holder adjacent the side portion of the opposite lateral frame.

6. A portable receptacle including a bag and a frame therefor, said bag having side 55 walls and externally concave gussets at the ends of the bag, said frame having means including a plurality of sets of arms, the arms of at least one set crossing each other so that pressure exerted on said set of crossed arms 60 for moving the same toward each other causes an opening movement of said receptacle, said crossed arms having portions resiliently engaging each other and being disengageable by said pressure, each set of said 65 arms being positioned within a concave space

externally of the bag, whereby said pressure is exerted through said side walls.

7. A portable receptacle including a bag and a frame therefor, said bag having side 70 walls and externally concave gussets at the ends of the bag, said frame having means including a plurality of sets of arms, the arms of at least one set crossing each other so that pressure exerted on said set of crossed arms for moving the same toward each other causes an opening movement of said receptacle, said crossed arms having portions resiliently engaging each other and being disengageable by said pressure, each set of said 75 arms being positioned within a concave space externally of the bag, whereby said pressure is exerted through said side walls, and said arms substantially following the contour of the side walls of the bag.

8. A portable receptacle including a bag and a frame therefor, said bag having side 80 walls and externally concave gussets at the ends of the bag, said frame having means including a plurality of sets of arms, the arms of at least one set crossing each other so that pressure exerted on said set of crossed arms for moving the same toward each other causes an opening movement of said receptacle, each set of said arms being positioned 85 within a concave space externally of the bag, whereby said pressure is exerted through said side walls.

9. In a frame of the character described, a pair of bow-shaped frame members pivoted together at their extremities with intermediate portions of the frame members movable into proximity with each other when the frame members move toward each other and the ends of the frame members crossing each other when the frame members are in closed condition, and an interlocking connection between the crossed ends becoming active during closing movement to retain the frame members in closed condition.

10. A frame for hand bags and other containers including a pair of frame members, each having a pair of side arms and a bar connecting corresponding ends of the arms, the free ends of the arms of one frame member being movably connected to the free ends of the arms of the other frame member, the frame members being of a configuration to present the side arms of the frame members in crossed relation when the bars are in abutting relation, and separable connections between the arms to retain them in crossed relation by snap action operative upon closing of the frame members.

11. A frame for a container of the character described comprising complementary bow shaped members pivoted together at their extremities and having their middle portions in juxtaposition with their ends spaced to permit one member to pass between the other, the end portions at each end 125

crossing between the adjacent pivot and middle portion, and provided with notches at the crossing point in closed position to retain said members in closed position by snap action.

12. A device for holding closed the opening of a receptacle and for manipulating the same comprising a pair of elements for association with the walls of the receptacle and having provision for attaching them near one end adjacent the opening therein, said members in the closed position of the parts being crossed between their ends and presenting opposed body portions inwardly of the crossing thereof, and being substantially rigid in the plane of the crossing, whereby they may be manipulated by pressure, said members being laterally resiliently yieldable and releasably interlocking at the crossing.

13. A device for holding closed the opening of a receptacle and for manipulating the same comprising a pair of elements for association with the walls of the receptacle and having provision for attaching them near one end adjacent the opening therein, said members in the closed position of the parts being crossed between their ends and presenting opposed body portions inwardly of the crossing thereof, and being substantially rigid in the plane of the crossing, whereby they may be manipulated by pressure, said members being laterally resiliently yieldable and having opposed faces shaped to contact at the crossing to hold the parts closed and to bear on each other with reduced pressure after release at the crossing during opening movement.

14. A holder having sides openable and closable in such manner as to change their angular relation to each other, two frame members angularly movable with respect to each other having portions crossing each other, a portion of one frame member being anchored to one edge portion of the holder and a portion of the other frame member being anchored to the other edge portion of the holder, the crossing portions of the two frame members being intermediate the mouth edges of the holder and the bottom of the holder, at least a portion of one frame member intermediate the crossing portions and the bottom of the holder being exposed to the action of finger pressure in a direction toward the other frame member, the said frame members being so located as to be unobstructed in their movements by the contents of the holder.

15. A frame for a container of the character described comprising two bow-shaped members, each member having a middle portion and two end portions, the end portions at a point remote from the aforesaid middle portions having connecting means to provide for relative angular movement, said end portions crossing each other between the middle portion and the aforesaid means, one end portion at a crossing point being provided

with means adapted to come into engaging and holding relation to the juxtaposed end portion as they approach said crossing point and releasable by movement in the opposite direction.

16. A holder having a frame and front and back cover portions openable and closable about the bottom edge and presenting a mouth portion, said frame comprising complementary bow-shaped members having crossed end portions hinged together adjacent to their extremities, the middle portions of said members, each being secured to the top edge of the opposite cover portion respectively, and said holder when in closed position having the greatest distance between adjacent end portions in proximity to the points of connection and also having the middle portion of one frame member substantially aligned with the wider parts of the end portions of the opposite frame member with both middle and end portions generally coincident with the planes of the front and back cover portions.

17. A portable receptacle including a holder and a frame therefor, said holder having side walls, said frame having means including a plurality of sets of arms, the arms of at least one set crossing each other and being exposed at the end of the holder so that pressure exerted on said set of crossed arms for moving the same toward each other causes an opening movement of said holder, said crossed arms having portions resiliently engaging each other and being disengageable by said pressure, and each set of arms being so located as to be unobstructed in their movements by the contents of the holder.

18. A portable receptacle including a holder and a frame therefor, said holder having side walls, said frame having means including a plurality of sets of arms, the arms of at least one set crossing each other so that pressure exerted on said set of crossed arms for moving the same toward each other causes an opening movement of said holder, said frames having resilient catch means and being disengageable by said pressure, each set of said arms being so located as to be unobstructed in their movements by the contents of the holder and said arms substantially following the contour of the side walls of the holder.

19. A portable receptacle including a holder and a frame therefor, said holder having side walls, said frame having means including a plurality of sets of arms, the arms of at least one set crossing each other so that pressure exerted on said set of crossed arms for moving the same toward each other causes an opening movement of said holder, each set of arms being positioned in a zone removed from the containing area of the holder and between the side walls, and said pressure being exerted through said side walls.

20. A portable receptacle including a

holder and a frame therefor, said holder having side walls, said frame having means including a plurality of sets of arms, the arms of at least one set crossing each other so that 5 pressure exerted on said set of crossed arms for moving the same toward each other causes an opening movement of said holder, each set of arms being positioned in a zone removed from the containing area of the 10 holder and between the side walls, and hinge means constructed and arranged for loosely connecting said crossed arms thereby permitting free pivotal movement of said arms toward and away from each other.

15 21. A portable receptacle including a holder and a frame therefor, said holder having side walls, said frame having means including a plurality of sets of arms, the arms of at least one set crossing each other so that 20 pressure exerted on said set of crossed arms for moving the same toward each other causes an opening movement of said holder, each set of arms being positioned in a zone removed from the containing area of the holder 25 and between the side walls, hinge means constructed and arranged for loosely connecting said crossed arms thereby permitting free pivotal movement of said arms toward and away from each other, and fastening 30 means carried by said arms and providing the sole means for holding said arms in a given position.

22. A frame for a container of the character described, comprising complementary 35 bow-shaped members having portions intermediate of their ends forming a closure for the container with their end portions connected at a point remote from the middle portions so as to provide angular movement 40 with respect to each other and spaced to permit the end portions of one member to pass the end portions of the other frame member, the end portions at each end crossing between the adjacent connection and middle 45 portion, one of said bow-shaped members having fastening means becoming active upon movement to some crossing point to engage and hold the other bow-shaped member, and releasable upon movement in the 50 other direction.

23. A holder having sides openable and closable in such manner as to change their angular relation to each other, two frame members angularly movable with respect to 55 each other having portions crossing each other, a portion of one frame member being anchored to one edge portion of the holder and a portion of the other frame member being anchored to the other edge portion of the 60 holder, the crossing portions of the two frame members being intermediate the mouth edge of the holder and the bottom of the holder, at least a portion of one frame member intermediate the crossing portions and the bottom of the holder being exposed to the ac-

tion of finger pressure in a direction toward the other frame member, the said frame members being so located as to be unobstructed in their movements by the contents of the holder, and cooperating means carried by the 70 two frame members constructed and arranged to come into engaging and holding relation as the sides of the holder approach a closed position.

24. A holder having sides openable and closable in such manner as to change their angular relation to each other, two frame members angularly movable with respect to each other having portions crossing each other, a portion of one frame member being anchored to one edge portion of the holder and a portion of the other frame member being anchored to the other edge portion of the holder, the crossing portions of the two frame members being intermediate the mouth 75 edges of the holder and the bottom of the holder, at least a portion of one frame member intermediate the crossing portions and the bottom of the holder being exposed to the action of finger pressure in a direction toward the other frame member, the said frame members being so located as to be unobstructed in their movements by the contents 80 of the holder, said frame members being pivotally connected at their lower ends and the 85 sides of the holder being openable by such pressure applied on the crossed portions between the crossing point and pivotal connection and closable by such pressure in the same direction at the opposite side of the 90 crossing point.

25. A holder having a frame and front and back cover portions openable and closable about the bottom edge and presenting a mouth portion, said frame comprising complementary bow-shaped members having portions intermediate of their ends forming a closure for the container with their end portions connected at points remote from the middle portions so as to provide angular 100 movement with respect to each other and spaced to permit the end portions of one member to pass the end portions of the other frame member, the end portions of each end crossing between the adjacent connection and middle 110 portion, one of said bow-shaped members having fastening means becoming active upon movement to closed position of the holder to engage and hold the other bow-shaped member and releasable upon movement in the other direction and said holder when in closed position having the end portions of the frame members located entirely between two planes, each of which planes touches the outer edge of one of the end portions adjacent to the point of connection and the outer edge of the mouth of the holder.

In testimony whereof I affix my signature.
LEO PAWLICEK.
